UNITED STATES PATENT OFFICE

PAUL EDMOND GAIRE, OF NEW YORK, N. Y.

HAIR-TREATING IMPLEMENT

Original application filed October 8, 1928, Serial No. 311,161. Divided and this application filed February 9, 1929. Serial No. 338,777.

This invention is directed to an improvement in hair treating implements and is directed particularly to a protector to be arranged between the box and the head of the patient.

Invention contemplates for use in conjunction with the box described a protector designed to at all times interpose between the box and head of the patient the heat insulating medium which will properly protect the head of the patient against any heat sensation whatever. The protector is designed to engage the strands of hair which are wound upon the pin 9 within the box or container and to immediately underlie the box and rest upon the head of the patient. 55

In connection with hair curling machines, the hair of the patient is wound about a curling pin and the latter placed in a box or container to which steam and air or other heating medium is admitted for the purpose of imparting a permanent wave or curl to the hair. While undergoing treatment, a comparatively large number of such boxes are used, each containing a strand of hair and as these are grouped comparatively close to the head of the patient, there would be a decided and generally unpleasant sense of heat on the head of the patient if means were not provided for preventing this condition. 60

The protector comprises two sections 21 and 22, the former being of double thickness, preferably by bending a strip on a longitudinal median line to present two sections 23 and 24 at one edge. The section 22 is a single strip. These sections are hingedly connected at 25 and a swinging latch 26 is connected to the free end of one section to overlie and engage the free end of the other section 65

to hold the sections in connected relation. 70

The primary object of the present invention is the provision of a protector designed particularly for use with the containers or boxes of this invention and serving to protect the head of the customer against the heat necessarily incident to the treatment. These protectors are designed to provide a more or less firm grip on the strand of hair in the particular box, rest squarely on the head of the patient immediately beneath the box and so insulated as to prevent the patient from feeling the effects of the heat in the box. 75

Each section 21 and 22 is covered by a thin strip of rubber indicated at 27, the rubber in each instance overlying the meeting edges of the strips. Each strip is provided on one side with a layer of felt indicated at 28, the felt being of substantial thickness. If desired and as preferred, the sections 21 and 22, which are preferably of metal, are formed with perforations 29 and both the rubber layer and felt are secured to the respective sections by stitching 30 which passes through the perforations 29 in the metallic sections. 80

In the use of this protector, after the hair has been wound on the pin and placed within the box, the sections of the protector are spread apart and passed over the strand of hair in the particular box between the head of the patient and the box. In this application of the protector, the felt layers 28 are 85 placed next the head of the patient. The sections are then closed and the latch moved into operative position. The latch is arranged to have a somewhat wedging action so as to tend to force the free edge of the section 22 in between the plates 23 and 24 of the section 21, as indicated in Figure 4. As these edges are covered with rubber sheets 27, this action tends to tightly confine the hair between the sections against any possibility 90

5 In connection with hair curling machines, the hair of the patient is wound about a curling pin and the latter placed in a box or container to which steam and air or other heating medium is admitted for the purpose of imparting a permanent wave or curl to the hair. While undergoing treatment, a comparatively large number of such boxes are used, each containing a strand of hair and as these are grouped comparatively close to the head of the patient, there would be a decided and generally unpleasant sense of heat on the head of the patient if means were not provided for preventing this condition. 10

15 The primary object of the present invention is the provision of a protector designed particularly for use with the containers or boxes of this invention and serving to protect the head of the customer against the heat necessarily incident to the treatment. These protectors are designed to provide a more or less firm grip on the strand of hair in the particular box, rest squarely on the head of the patient immediately beneath the box and so insulated as to prevent the patient from feeling the effects of the heat in the box. 20

25 The invention is illustrated in the accompanying drawings, in which:

Figure 1 is a perspective view of the improved protector, parts being shown in relatively open relation.

Figure 2 is a broken plan view of the improved protector.

Figure 3 is a view similar to Figure 2, viewed from the opposite side.

Figure 4 is an enlarged section on line 4-4 of Figure 3.

45 In the use of boxes or containers for the treatment of hair, particularly where as is contemplated in the present invention the treating fluid is steam, there is considerable liability that, in the absence of protection against such heat, the head of the patient will be uncomfortably warm. In order to 50 avoid any possibility of this, the present in-

of separation and yet through the soft resilient character of the rubber sheets 27, there is no liability of injury to the strands of hair.

The protector completely underlies the 5 particular box and through the medium of the felt layers 28, insulates the head of the patient from any appreciable heat effects from the box or container.

It is of course to be understood that the 10 respective protectors are arranged one beneath each box used during the treatment and it is also apparent that the protectors may be readily and quickly applied or removed without loss of time on the part of the attendant and without any inconvenience whatever to the patient.

This application is a division of my application filed October 8, 1928, Serial No. 311,161.

20 What is claimed to be new is:

1. A protector to underlie the boxes used in hair curling machines, comprising pivotally connected sections, one being of double thickness and formed to permit edge separation, and the other a single strip adapted to be forced between the parts of the section of double thickness, means for connecting the sections to cause the strips to confine the hair between them, and heat insulating 30 sections connected to the strips.

2. A protector to underlie the boxes used in hair curling machines, comprising pivotally connected sections, one being of double thickness and formed to permit edge separation, and the other a single strip adapted to be forced between the parts of the section of double thickness, a rubber strip overlying the meeting edges of each section, means to connect the sections to cause the rubber strips 35 and the cooperation of the sections to grip the hair, and heat insulating sections secured to the strips.

3. A protector to underlie the boxes used in hair curling machines, comprising pivotally connected sections, one being of double thickness and formed to permit edge separation, and the other a single strip adapted to be forced between the parts of the section of double thickness, a rubber strip overlying 45 the meeting edges of each section, means to connect the sections to cause the rubber strips and the cooperation of the sections to grip the hair, and a layer of felt secured to the similar side of each strip.

55 In testimony whereof I affix my signature.
PAUL EDMOND GAIRE. [L. s.]
